ERASER FOR MECHANICAL PENCILS

Arthur S. Dysart, Onoville, N. Y.

Application August 26, 1938, Serial No. 227,007
Renewed November 21, 1939

7 Claims. (Cl. 120—38)

This invention relates to pencils and particularly to an eraser feeding mechanism adapted primarily for pencils of the mechanical type.

An object of the invention is to provide an advancing means for an eraser permitting an elongated cylindrical eraser mounted axially within the pencil barrel to be gradually advanced outwardly as it becomes worn, and frictionally retained in any adjusted position within the body of the pencil.

Another object of importance of the invention is to provide a plurality of obliquely disposed rollers within the pencil barrel engaging the surface of the eraser so that rotation of the eraser relative to the barrel will force the eraser axially within the barrel, the direction of movement being dependent upon the direction of rotation of the eraser relative to the pencil.

A feature that is important is that the obliquely disposed rollers may be retained in position within openings provided therefor in a thin sleeve fitting rotatably within the barrel of the pencil. The rollers may, however, be individually supported with an enlarged portion of the barrel.

With the above and other objects in view the invention includes the features of construction and operation set forth in the following specification and illustrated in the accompanying drawing.

In the accompanying drawing annexed hereto and forming a part of this specification, I have shown the invention embodied in a mechanical pencil of conventional form, but it will be understood that the invention can be otherwise embodied and that the drawing is not to be construed as defining or limiting the scope of the invention, the claims appended to this specification being relied upon for that purpose.

In the drawing:

Fig. 1 is an outside view of one end of a pencil within which the invention may be embodied.

Fig. 2 is a longitudinal sectional view of one form of my eraser advancing mechanism.

Fig. 3 is a transverse sectional view taken on the plane of line 3—3 in Fig. 2.

Fig. 4 is a view similar to Fig. 2 but showing a modified form of the invention.

Fig. 5 is a sectional view of the oblique rollers within their retainer prior to insertion within the pencil.

Fig. 6 is a view showing a metal strip from which the roller retaining member may be formed, one of the rollers being shown in place therein.

Fig. 7 is a transverse sectional view taken on plane of line 6—6 in Fig. 6, and

Fig. 8 is a longitudinal sectional view of a modified form of the invention.

In the above mentioned drawing there have been shown several embodiments of the invention which are now deemed preferable, but it is to be understood that changes and modifications may be made within the scope of the appended claims without departing from the spirit of the invention.

Briefly, and in its preferred aspect, the invention may include the following principal parts: First a pencil barrel; second, an elongated cylindrical eraser inserted within an end of the pencil barrel or body portion; third, a plurality of spaced oblique rollers within the pencil barrel and engaging the surface of the eraser; and fourth, a retainer for the rollers disposed within the pencil barrel and surrounding the eraser.

Referring more in detail to the figures of the drawing there is shown a pencil body portion or barrel 10 which may be of any preferred form such as a thin sleeve or tube. In an open end of the body portion 10 is inserted an eraser 11 which as shown is cylindrical and of substantial length. In the form of the invention shown in Figs. 1 and 2 the pencil barrel 10 has an inner sleeve 12 closely fitting therein. Preferably and as shown in Fig. 2 the end of the barrel 10 is reduced in diameter as at 13 so that its inner wall will closely engage the eraser for a portion of its length, there being formed an annular recess within the barrel within which the eraser advancing means may be disposed. On the outside of this reduced end 13 there may be placed a removable cap of any form (not shown) to enclose and protect the eraser 11. Openings 9 may be cut into this reduced barrel portion 13 so that the eraser 11 may be grasped and advanced when worn away.

Within the barrel 10 is mounted a thin annular sleeve 14 which may loosely surround the eraser 11 and be disposed between the end of inner sleeve 12 and the end wall of barrel 10 at its full diameter. This sleeve 14 as shown is held against endwise movement within the barrel and is provided with oblique slots 15, there being three or four of these slots disposed equally about the circumference of this sleeve. Small tubular rollers 16 fit loosely within these slots and are of such diameter that they are in firm contact with the eraser 11 and with the inner cylindrical surface of the barrel 10. In order to retain the rollers 16 in position a retaining wire 17 of spring 55

steel or other suitable metal may pass through the central holes of the rollers and around the sleeve 14. As shown in Fig. 2 the central portion of the sleeve 14 is reduced in diameter to allow ample space for the retainer wire 17 which may conform closely to the outer surface of the sleeve 14 and be held from contacting the inner surface of the barrel 10.

In Fig. 4 there is shown a slightly modified form of sleeve 18 replacing sleeve 14 and serving to space the rollers 16 properly about the eraser 11 in the same manner by means of obliquely disposed slots therein. In this form of sleeve however the periphery is not continuous but is interrupted by a slot extending obliquely throughout the length of the sleeve. Prior to insertion of the sleeve 18 into its position within the barrel 10 the diameter of the sleeve 18 may be extended as shown in Fig. 5. By compressing the sleeve to close the gap and form a substantially complete circle the sleeve may be inserted within a barrel such as shown in Fig. 4 in which the sleeve fits within an enlarged recess formed integrally or by a spinning operation within the barrel 19.

To make up sleeves 18 for insertion within barrels 19 in a manner permitting them to be formed in multiple lengths which may be cut apart for individual sleeves 18 as needed the following may be employed. A long strip of thin sheet metal 20 may be slotted as shown at 21 at spaced distances and at the proper oblique angle. Within the slot 21 may be placed tubular rollers 22 of the proper diameter and length to fit easily therein and function as indicated above. To retain the rollers 22 in proper position they may be mounted upon short lengths of wire 23 extending through their central holes and beyond the ends of the rollers 22. To hold the wires 23 in place which as shown are separate for each roller the longitudinal edges 24 of the strip 20 may be doubled over and crimped down upon the flat surface of the strip. Short lengths of the strip 20 with the rollers 22 mounted therein may be cut off and bent into annular form substantially as indicated in Fig. 5.

In Fig. 8 there is shown a modified form of the means for supporting oblique rollers 16 in their places. In this embodiment the rollers 16 are retained individually in place by a separate supporting wire passing centrally through each roller. The ends of each wire pass through the wall of the barrel 17, which may be similar to that shown in Fig. 4, and headed over as indicated.

55 I claim as my invention:

1. An eraser holder for mechanical pencils comprising in combination, a barrel, a cylindrical eraser inserted therein, and rollers disposed obliquely within the barrel and frictionally en-

gaging the eraser, whereby rotation of said eraser within said barrel will advance said eraser axially.

2. An eraser holder for mechanical pencils comprising in combination, a pencil barrel, a cylindrical eraser inserted therein, a sleeve within the barrel retained against axial movement, rollers disposed within oblique slots within said sleeve and frictionally engaging said barrel and eraser, whereby rotation of said eraser relative to said barrel will advance said eraser axially. 10

3. An eraser holder for mechanical pencils comprising in combination, a pencil barrel, a cylindrical eraser inserted therein, a sleeve within the barrel retained against axial movement therein and having spaced obliquely disposed slots in its walls, rollers disposed within said slots and frictionally engaging the eraser and inner wall of said barrel, a wire passing through central holes of said rollers and around said sleeve to retain said rollers in spaced relation to the eraser. 15

4. An eraser holder for pencils comprising in combination, a pencil barrel, an eraser inserted therein, obliquely disposed rollers disposed between and frictionally engaging said barrel and eraser, a retainer for said rollers comprising a thin metal sleeve, and individual wires retaining said rollers respectively within slots formed within said sleeve. 20

5. An eraser holder for pencils comprising in combination, a pencil barrel, an eraser inserted 30 therein, obliquely disposed rollers disposed between and frictionally engaging said barrel and eraser, a retainer for said rollers comprising a thin metal obliquely slotted strip having said rollers disposed and retained within said slots, 35 said strip being bent into annular form to fit within said pencil barrel.

6. An eraser holder for mechanical pencils comprising in combination, a barrel having openings therein adjacent the eraser end, a cylindrical eraser inserted therein, and rollers disposed obliquely within the barrel and frictionally engaging the eraser, whereby rotation of said eraser within said barrel will advance said eraser axially. 40

7. An eraser holder for mechanical pencils comprising in combination, a pencil barrel having openings therein adjacent the eraser end, a cylindrical eraser inserted therein, a sleeve within the barrel retained against axial movement 50 therein and having spaced obliquely disposed slots in its walls, rollers disposed within said slots and frictionally engaging the eraser and inner wall of said barrel, a wire passing through central holes of said rollers and around said sleeve to 55 retain said rollers in spaced relation to the eraser.

ARTHUR S. DYSART.
